W. C. BALDWIN,
ELECTRICAL DRIER FOR PAPER AND THE LIKE.
APPLICATION FILED JAN. 20, 1919.

1,401,303.

Patented Dec. 27, 1921.

INVENTOR
WILLIAM C. BALDWIN.

Feltens & Schaeffer & Co
ATTYS.

UNITED STATES PATENT OFFICE.

WILLIAM CHARLES BALDWIN, OF OTTAWA, ONTARIO, CANADA.

ELECTRICAL DRIER FOR PAPER AND THE LIKE.

1,401,303.

Specification of Letters Patent. Patented Dec. 27, 1921.

Application filed January 20, 1919. Serial No. 272,150.

To all whom it may concern:

Be it known that I, WILLIAM CHARLES BALDWIN, a subject of the King of Great Britain, and resident of the city of Ottawa, 5 in the Province of Ontario, Dominion of Canada, have invented certain new and useful Improvements in Electrical Driers for Paper and the like, of which the following is a specification.

10 This invention relates to improvements in electrical driers for paper and the like, and the objects of the invention are to provide a simple and effective device occupying small space, and by which paper or other material 15 may be rapidly and continuously dried. It consists essentially of a moving electrically heated screen conveyer constructed and arranged as shown in detail in the accompanying specification and drawings.

20 In the drawings:

Figure 1 is a sectional perspective view showing an embodiment of the invention.

Fig. 2 is a vertical sectional view of an alternative form of the invention.

25 In the drawings like characters of reference indicate corresponding parts in all the figures.

Referring to the drawings, A represents an electrical movable element, preferably in 30 the form of an endless conveyer or belt formed from wire mesh of brass or other suitable material and mounted between suitable rollers 10 and 11, the rollers being supported from suitable bearings 12 and 13, 35 the bearings on one side only of the rollers being shown on the drawings. The bearings 12 and 13 are supported from a suitable frame work 14 of wood or like insulating material whereby the bearings at opposite 40 ends will not be in electrical contact. The sheet of paper B to be dried is carried by the conveyer A which is electrically heated to a proper temperature. I prefer to heat the conveyer A by the use of a comparatively 45 low potential, providing one terminal 15 on the bearing 12, and the other terminal on the bearing 13, the current passing through the wire mesh of the conveyer, and thereby heating the same. I prefer to use a current 50 under 100 volts, direct or alternating as may be desired, the amount of current used being in proportion to the resistance of the conveyer and sufficient to attain the elevated temperature desired.

The conveyer A takes the place of the 55 drier felt and series of drying rolls usually employed in drying paper, and it will be found possible by its use to rapidly and efficiently dry a moving strip or sheet of paper.

60 It will be understood that the motion will be imparted to the conveyer A in any suitable way by any suitable driving mechanism connected to either or both of the rollers 10 and 11.

65 In the alternative form of the invention shown in Fig. 2 a series of pairs of rollers C and C¹, D and D¹, E and E¹ are employed, each provided with a conveyer C², D² and E² similar to the conveyer A, being all supported from the frame F. The strip of paper in this case may be fed, for instance, from right to left along the upper conveyer C², then between the conveyers C² and D², 70 then between the conveyers D² and E², and 75 then along the bottom of the conveyer E², in this way both sides of each conveyer will be utilized in imparting heat to the sheet of paper.

80 To prevent undue radiation of heat from the device a casing G may be provided enclosing the various heating conveyers.

85 It will be observed that in the form of the invention shown in Fig. 2 a conveying belt applies the heat to both sides of the paper, thereby effecting an extremely rapid drying of the same.

90 As many changes could be made in the above construction and many apparently widely different embodiments of my invention within the scope of the claim, constructed without departing from the spirit or scope thereof, it is intended that all matter contained in the accompanying specification and drawings shall be interpreted as illustrative and not in a limiting sense.

95 What I claim as my invention is:

In a drier, an endless belt formed of electric conductive material, means for passing an electric current through the belt to heat 100 the same.

In witness whereof I have hereunto set my hand in the presence of a witness.

WILLIAM CHARLES BALDWIN.

Witness:

RUSSEL S. SMART.
